(57) **CLAIM**

The ornamental design for a fixture adapted for use with a stability ball, as shown and described.

DESCRIPTION

FIG. 1 is a perspective view of a fixture adapted for use with a stability ball showing my new design;

FIG. 2 is a second perspective view thereof;

FIG. 3 is a first end elevational view thereof, the opposite second end elevational view being a mirror image of the first end elevational view;

FIG. 4 is a top plan view thereof; and,

FIG. 5 is a bottom plan view thereof.

The broken lines showing a stability ball in FIG. 1 illustrate environmental structure and form no part of the claimed design.

1 Claim, 3 Drawing Sheets

FIG. 1

FIG. 2
